UNITED STATES PATENT OFFICE.

EDWIN H. BELL, OF CHICAGO, ILLINOIS.

TIE PLATE.

Application filed February 13, 1926. Serial No. 88,012.

This invention relates to improvements in tie plates and the object is to produce a plate in which the weight is reduced by removal of metal from the bottom, at places where it may be spared without impairing the gripping contact with the tie upon which it is placed; a plate which shall have its thickest body portion below the line on the top surface where the side margins of the rail flange will bear, and where plates usually tend to buckle and break; and a plate which has a plurality of undulations, grooves or recesses in the central area, which area is intermediate the ends and extends transversely of the plate.

To the accomplishment of these objects and the attainment of the advantages thereof, which will become manifest as I proceed with this specification, my invention consists in the devices and combinations of devices illustrated, described and more particularly pointed out in the claims hereto appended.

In the accompanying drawings:

Figure 1 is a view in perspective, of a tie plate embodying my invention.

Figure 2 is a plan view, enlarged, of the bottom of the plate, showing one form of the invention.

Figure 3 is a longitudinal, sectional view of the same, the section being taken in the vertical plane indicated by the dotted line 3-3 on Figure 2.

Figure 4 is a transverse, sectional view of the same, the section being taken in the vertical plane indicated at 4-4 on Figure 3.

Figure 5 is a plan view of the bottom of the plate showing a modified form.

Figure 6 is a transverse, sectional view of this modification, the section being taken in the vertical plane indicated by the dotted line 6-6 on Figure 5.

Figure 7 is a bottom plan view of another modification, and,

Figure 8 is a transverse, sectional view of this modification, the section being in the vertical plane indicated by the dotted line 8-8 on Figure 7.

In said drawings: the plate, designated as a whole by the letter A, has a top rail bearing surface 1, which may or may not be canted, crowned, plain or configurated. In this instance, I have shown the surface 1 as plain and as canted. The top is provided with the usual rail abutting shoulder 2 formed by the face of the transversely and upwardly extending rib 3. The top of the

plate is tapered somewhat toward each end, as indicated at 4 and 5.

The bottom of the plate is recessed, inwardly from each end and transversely from side to side, as shown at 6 and 7. The surface of the bottom of the plate immediately adjacent the recessed end portions, and by reason of the arrangement of the intermediate central area presently to be described, constitutes what I herein designate as relatively narrow, initial tie bearing surfaces 8, which extend transversely across the bottom of the plate.

These surfaces 8 will be located below the shoulder 2 against which the outer rail base flange bears, and below that point on the plate top where the side of the other base flange of the rail rests; thus the body of the plate contains the maximum of metal where thickness is most needed.

Upon these surfaces 8 and in the plane of these crucial points, I prefer to place a shallow, downwardly pointed rib 9, preferably blunt or rounded rather than having a sharpened edge, which rib extends lengthwise of the surface 8; that is, transversely of the plate. The rib 9, as shown, is located centrally of the surface 8, and in the first instance merely indents the tie and serves to hold it in position, while the rail is being set and spiked. The ribs 9 do not interfere with the function of the surfaces 8 as initial tie bearing surfaces.

Intermediate the transverse surfaces 8, 8, is what I herein designate as the central or median recessed area, and in which I locate a plurality of undulations, grooves or recesses 10. The grooves 10, 10, extend longitudinally of the plate and, preferably, in parallel relation, and are deeper at one end than the other. The deep end is of a flattened, arcuate contour 11, as clearly disclosed in Figs. 2 and 4, and abuts the inside, marginal wall of the part 8. The median surface line of each groove 10, therefore, will slant or incline from a plane coincident with the plane of the surface 8 into the central area of the plate, to the deepest part, thus forming a groove of gradually increasing depth, as clearly demonstrated by Figure 3.

These grooves or undulations 10, 10, may be variously grouped and arranged to suit special conditions or engineering requirements of the railroads upon which the plates will be used.

I have shown several, but not all of these

various forms. In Figures 2, 3 and 4, I have shown the grooves 10 arranged with the deep part of one groove nearest the recessed end 6 and the deepest part of the alternate groove nearest the recessed end 7.

In the modification shown in Figures 5 and 6, I have arranged four grooves adjacent each other, with their deep parts near one end of the plate, and the other group 10 of four grooves with their deepest part near the other end of the plate.

In Figures 7 and 8, the grooves are arranged in groups of two and similarly, the groups extend alternately towards opposite 15 ends of the plate. While I prefer to have the parallel grooves extend, as shown, longitudinally of the plate, it will be manifest that this is not mandatory and that an inclination which maintains a substantially 20 longitudinal direction, will conform to the invention, and is to be included within the scope of the appended claims. It will be understood that several advantages result 25 from constructing a tie plate in accordance with my invention. Making the grooves of gradually increasing depths enables me to remove a desirable amount of metal without weakening the plate; and by making the groove deeper at its deepest end than the 30 depth of a groove of the same width, the bottom of which is parallel with the bottom line of the plate, enables me to remove a greater amount of metal by using the inclined bottom groove than by using a flat 35 bottom groove. By alternating one or more of the grooves with inclined bottoms, I do not weaken the plate at those points which are below the side margins of the rail flanges when the rail is on the plate; the length of 40 the grooves being such that the plate is of proper thickness adjacent the deepest part of the groove, thereby counteracting any tendency to break or buckle by reason of the depth of the groove.

45 By the construction illustrated I also attain great holding power upon the tie and the tendency of the plate to shift upon the tie is reduced to a negligible quantity by reason of the alternate arrangement of the 50 grooves.

I claim as my invention:

1. A tie plate having a rail bearing surface and a transversely disposed rail abutting shoulder on its top, and provided in the 55 central area of its bottom with a plurality of longitudinally extending grooves of varying depth from end to end.

2. A tie plate having a rail bearing surface and a transversely disposed rail abutting shoulder on its top, and provided in the 60 central area of its bottom with a plurality of longitudinally extending grooves of varying depth from end to end, the grooves running in opposite directions.

65 3. A tie plate having on its top a rail

bearing surface and a transversely disposed rail abutting shoulder, and provided in the central area of its bottom with a plurality of longitudinally extending grooves of gradually increasing depth each terminating in a 70 flattened, arcuate surface.

4. A tie plate having on its top a rail bearing surface and a transversely disposed rail abutting shoulder, and provided in the central area of its bottom with a plurality of 75 longitudinally extending grooves of gradually increasing depth each terminating in a flattened, arcuate surface, the deep portion of some grooves being on one side and some on the other side of the transverse, median 30 line of the plate.

5. A tie plate having on its top a rail bearing surface and a transversely extending rail abutting shoulder, the body of the plate being thickest at those parts below the 85 side margins of the rail base, and provided on its bottom in the central area intermediate said thickened parts, with a plurality of longitudinally extending recesses of gradual- 90 ly increasing depth.

6. A tie plate having on its top a rail bearing surface and a transversely extending rail abutting shoulder, the body of the plate being thickest at those parts below the side 95 margins of the rail base, and provided on its bottom in the central area intermediate said thickened parts, with a plurality of longitudinally extending recesses of gradually increasing depth, the deep part of each recess having a flattened arcuate surface. 100

7. A tie plate having on its top a rail bearing surface and a transversely extending rail abutting shoulder, the body of the plate being thickest at those parts below the side 105 margins of the rail base, and provided on its bottom in the central area intermediate said thickened parts, with a plurality of longitudinally extending recesses of gradually increasing depth, and extending in opposite directions. 110

8. A tie plate having on its top a rail bearing surface and a transversely extending rail abutting shoulder, and provided on its bottom with recessed end portions and a central, recessed area, whereby the thickest 115 parts of the plate body lie transversely beneath the side margins of the rail flanges, and provided in said central area with a plurality of longitudinally extending recesses or grooves of gradually increasing depth. 120

9. A tie plate having on its top a rail bearing surface and a transversely extending rail abutting shoulder, and provided on its bottom with recessed end portions and a central, recessed area, whereby the thickest parts of the plate body lie transversely beneath the side margins of the rail flanges, and provided in said central area with a plurality of longitudinally extending recesses or grooves 125 of gradually increasing depth, the deep part 130

of each recess having a flattened, arcuate surface.

10. A tie plate having on its top a rail bearing surface and a transversely extending rail abutting shoulder, and provided on its bottom with recessed end portions and a central, recessed area, whereby the thickest parts of the plate body lie transversely beneath the side margins of the rail flanges, and provided in said central area with a plurality of longitudinally extending recesses or grooves of gradually increasing depth, and extending in opposite directions.

11. A tie plate having on its bottom, re-

cessed end portions and a central, recessed 15 area, and two relatively narrow, initially tie bearing surfaces extending transversely of the plate and separating the end recesses from the central area, and a plurality of grooves in the central area and extending 20 longitudinally, in opposite directions, each groove being of gradually increasing depth as it extends from one transverse tie bearing surface toward the other transverse surface.

In testimony, that I claim the foregoing 25 as my invention I affix my signature, this 10th day of February, 1926.

EDWIN H. BELL.
